PEYTON S. COLES, OF ATLANTA, GEORGIA

WHIRLIGIG

Application filed January 29, 1930. Serial No. 424,352.

This invention relates to whirligigs or bandelores and aims to provide an improved wheel or rotating member so shaped and designed as to require a great deal of skill to operate successfully.

Other aims and advantages of the invention will appear in the specification, when considered in connection with the accompanying drawings, wherein:

Fig. 1 is a side elevation of a whirligig embodying the invention;

Fig. 2 is an edge view of the device shown in Fig. 1; and

Fig. 3 is a sectional view taken on the line 3—3 of Fig. 1.

Referring particularly to the drawing, the rotating member is there shown as being in the form of similar, elongated, substantially flat bars 10 connected at their centers by a suitable shaft such as the bolt 11. In this example, a small washer 12 on the bolt is interposed between the bars to hold them spaced so that the usual twisted cord 13 having a finger loop 14 may be wound on the washer 25 between the bars.

The inner or adjacent side and end edges of the bars are shown as being rounded or beveled so as to guide the cord 13 to wind on the shaft or washer in somewhat the same manner as the flared groove of an ordinary, disk-shaped wheel. However, the operator has to exercise considerable skill and agility to keep the cord in a plane approximately at right angles to the center of the shaft or in 35 the plane of rotation so as to prevent it from getting in the path of one of the arms of the bars.

When the bars or arms are at right angles as shown, a beginner can soon learn to make 40 the wheel wind and unwind upon the cord by properly timing or co-ordinating his hand movements with the up and down movements of the wheel and keeping the cord in the plane of rotation of the wheel. The operation 45 may be made more difficult and intriguing by varying the angularity of the bars. In this example, the bars may be adjusted by turning one of them on the shaft and tightening the nut. Thus, they may be adjusted so 50 that they are parallel and thereby make it

very difficult to keep the wheel in motion because of the tendency to wobble.

It will be understood that the string or cord 13 must first be wound on the shaft and that the operator will place the loop on one finger. Then the wheel is dropped or thrown so that it unwinds itself and acquires sufficient momentum to re-wind the cord in the opposite direction. When the wheel is rotated quite fast by an adapt operator it simulates a boomerang. To enhance its appearance, the arms may be painted different colors.

Obviously, the present invention is not restricted to the particular embodiment thereof herein shown and described.

What is claimed is:

A whirligig comprising, in combination, a pair of elongated, flat bars having control openings; a bolt passing through the openings; a washer on the bolt between the bars providing a winding shaft; a nut on the bolt adapted to grip the bars against the washer; and a cord adapted to be wound on the shaft, said bars having their inside edges beveled to guide the cord between them.

In testimony, that I claim the foregoing as my own, I have hereto affixed my signature.

PEYTON S. COLES.
